LAMP BASE

Ralph B. Thomas, Beverly, Mass., assignor to Sylvania Electric Products Inc., Salem, Mass., a corporation of Massachusetts

Application August 21, 1945, Serial No. 611,747

4 Claims. (Cl. 176—122)

1

This invention relates to discharge lamps and particularly to such lamps which are bent into curved forms and having their ends in opposed relation.

In lamps of the type indicated, it is necessary to provide special means for making the necessary connections for energizing the lamp. It is an object of the present invention to provide means for readily connecting the lamp to a source of power.

A further object of the invention is to provide a bent tubular lamp having a base joining its ends which is rotatable into a plurality of positions.

A further object of the invention is to provide in a bent tubular lamp having its ends disposed in opposed relation, a base which is readily applied to the lamp at a minimum cost.

A further object of the invention is to create a greater transmission of incident light emitting from the lamp.

A further object of the invention is to obtain a complete circle of light with minimum interruption caused by the base.

A feature of the invention is the use of a transparent or translucent plastic, etched or roughened on its surface.

Another feature of this invention is the use of light-reflecting insulating material on the lead wires.

Still another feature of the invention is that no cement is used to secure the lamp to the base.

An advantage of the invention is that there is a greater transmission of light from the lamp.

Other objects, features, and advantages of the invention will be apparent from the following description taken in conjunction with the drawing in which:

Figure 1 is a perspective view of a lamp embodying the invention;

Figure 2 is a longitudinal sectional view through the lamp base and socket; and

Figure 3 is a longitudinal sectional view similar to Figure 2 showing a different embodiment of the invention.

Figure 1 shows a circular lamp 1 having a lamp base 2 and conductor pins 3.

In Figure 2 the circular lamp 1 has end pieces 4 which desirably are parallel and symmetrical disposed in respect to a radius from the center of the lamp circle. The lamp base 2 is constructed of transparent or translucent plastic material in the form of a hollow cylinder divided longitudinally into two sections 5 and 6, these sections desirably being molded or otherwise formed

of insulating material and are held together by any suitable means such as the screw 7, the head of which is seated in portion 5 and having its other end threaded in the part 6. Such construction permits the lamp base to be assembled upon the lamp. A pair of dowel-shaped projections 17 are formed along the edges of the section 5 of base 2 and holes to match these projections 18 are formed in section 6 to prevent relative lateral movement thereof.

The ends of the base 2 are formed to present chamber recesses 8 within which the ends of the lamp are loosely received. The ends of the lamp project a substantial distance into the recesses 8 to insure the base will not become detached from the lamp. In the form of the invention shown in Figure 2 a relatively large central chamber 9 is formed within which the flexible lamp lead wires 10 are received. The interior surface of the chamber portion 9 may be etched or sandblasted as shown in Figure 2 or ribbed, fluted, or otherwise roughened as shown in Figure 3.

The ends of the lamp are, or may be, of standard construction having a reentrant flare portion 11 and a press portion 12 within the tube and supporting the lamp electrodes 13. The lead wires 10 are preferably covered with a light-reflecting electrical insulating material and are soldered to the inner ends of a pair of conducting pins 14, which are staked or molded in position in the base section 6 and are spaced the correct distance to be received in a socket made to receive them not shown in the drawing. Either two or four pins may be employed depending upon the type of lamp used and its circuit requirements.

It is desirable that the base 2 be restricted in its rotation to prevent excessive twisting of the lead wires. An angular adjustment of 180° is sufficient to adapt the lamp to any installation.

A desirable means for accomplishing this end is to form a projection 15 upon the end face of the lamp at or near its periphery. Stop shoulders are provided which engage the projection 15 at the limit of the travel of the base 2. Stop shoulders may be provided in any suitable manner. As illustrated in the drawing the portion of at least one of the recesses 8 formed in the section 6 of the base 2 is relatively shallow in depth while that portion formed in the section 5 is of greater depth and sufficient to receive projection 15. The difference in depth between the two portions of the recesses 8 presents stop shoulders 16 which engage the projection 15.

A base of the type herein described may read-

ily be molded or otherwise formed from the many thermoplastic or thermosetting plastic materials now in general use. It is generally more desirable however, to use those materials which are thermosetting since they are more stable under heat. If the base is formed of a transparent material it is desirable to etch or sandblast the surfaces to create a more even illumination from the base. An irregular surface such as caused by fluting, ribbing, or otherwise roughing the central chamber permits a larger surface for the incident light to fall upon and causes a greater and more even distribution of light emission through the socket. In order to reduce the amount of light absorption from the lead wires inside the socket a coating of light-reflecting electrical insulating material is applied to them. A base of the type herein described is favorably suited to the utilization of the incident light from the lamp since no cement is used in securing the lamp and socket thus leaving an unobstructed passage for light through the base.

This application is a continuation in part of my co-pending application Serial No. 585,260, filed March 28, 1945, which issued January 8, 1946, as United States Patent No. 2,392,785.

What I claim is:

1. In combination with a tubular discharge lamp of non-linear configuration having its ends disposed in spaced opposed relation, a hollow cy-

lindrical base member loosely embracing the ends of the lamp and extending therebetween whereby the base may be rotated thereon, said base being formed of translucent plastic, lead wires, covered with a light reflecting insulating material, connected to the lamp electrodes and extending into said base, contact pins projecting or opening into the hollow interior of the base with their other ends projecting outward for connection to a source of energy and means to connect said lead wires to said pins.

2. In combination with a tubular discharge lamp, a base of translucent material having lead wires covered with light-reflecting insulating material.

3. An electric discharge device for forming a complete circle of light emission, comprising a circular glass discharge tube sealed at each of its ends to form an incomplete circle, a tubular base of translucent material joining said ends and being substantially free of obstruction, to permit diffusion through said base of the light from the sealed ends of said tube.

4. The combination of claim 3, contact pins extending outward from said base, lead-in wires extending through the sealed ends of said tube to said pins, and a light-reflecting electrically-insulating material over said lead-wires to reduce light loss by said wires.

RALPH B. THOMAS.
